UNITED STATES PATENT OFFICE

CHARLES D. RAFFERTY, OF SAULT STE. MARIE, ONTARIO, CANADA

LOCOMOTIVE-WHISTLE-OPERATING MECHANISM

Application filed May 20, 1926. Serial No. 110,580.

This invention relates to an operating mechanism for the whistles of locomotives.

It is aimed to provide a novel construction employing a pneumatic cylinder adaptable 5 to any layout of standard whistle rigging and applicable to any type of whistle.

Another object is to provide a construction in which the said pneumatic means operates without springs or a stuffing box and in 10 which the piston moves to released position by the boiler pressure on the main whistle valve.

Another object is to provide a novel construction wherein the whistle may be actuated by fluid pressure for opening the steam valve without undue resistance by the hand lever.

Additional objects and advantages will become apparent from a consideration of the 20 description following taken in connection with accompanying drawings illustrating an operative embodiment.

In said drawings:—

Figure 1 is a view illustrating one form of 25 the invention in side elevation and in connection with a locomotive, suggested fragmentarily in dotted lines;

Figure 2 is a plan view;

Figure 3 is a central longitudinal sectional 30 view through the pneumatic operating means for the whistle valve, and

Figure 4 is a view similar to Figure 1 but of a modified form.

Referring specifically to the drawings, 35 and first to the form of Figures 1 to 3, the locomotive whistle is shown at A and is of the usual fluid-operated type. Its valve is operated by a lever a to which is pivoted a rod 10. Said rod 10 and accordingly the valve is 40 adapted to be operated either by hand through manipulation of a lever 11 having a handle 12, or by foot through operation of the valve 12', in the latter instance, controlling the entry of operating fluid through a pipe 13, 45 having connection with the main air reservoir, of the air brake system. The valve 12' is normally closed, but when depressed by the foot, opens and permits the compressed air to pass through the same.

50 Pipe 13 leads, as best shown in Figure 3,

to a nipple 14 of a cylinder 15, which as shown in Figures 1 and 2, may be conveniently located within a cab, for instance supported by a bracket 16 fastened to the cab and applicable over the nipple 14 of the cylinder 55 and being secured thereto through the medium of a nut 17 threaded to said nipple. The air inlet passageway through the nipple 14 is designated 18 and it leads to the chamber 19 of the cylinder. In said chamber, is a suitable piston 20. A vent or pressure release port 21 is provided through the wall of cylinder 15 on the low-pressure side of the piston. 23 designates the piston rod secured to piston 20 and slidably mounted 60 through a head 24 detachably screw threaded at 25 into the cylinder 15. Said rod 23 is pivotally connected at 27 to a cross lever 28, pivoted as at 29 to a bracket 30 connected to the cab C of the locomotive within which 70 the valve 12' is located. Lever 28 at one end as at 31 is pivotally connected to the rod 10 and at its other end may have a standard connection as at 32 to a snow plow.

Within the cab said lever 11 is disposed 75 and it has a rod 33 suitably journaled and provided with a crank 34 from which a pin 35 extends and is disposed in an elongated slot 36 in said rod 10. The pin 35 is normally at the forward extremity of slot 36, being so 80 maintained by a weighted connection as at 37 on rod 33, but of course other means may be substituted for said weight if desired.

Due to the construction described, the valve 85 of the whistle A may be operated from within the cab, by the operator with one foot depressing the valve 12', or through movement of one hand, moving the lever 11 downwardly at its free end. When the valve 12' is 90 operated, the compressed air passes through pipe 13, port 18 into chamber 19 behind the piston 20, thus moving said piston 20 forward and correspondingly moving the rod 23 which rocks the lever 28 and moves the lever 10 rearwardly. Thus operation of either 95 lever 11 or valve 12' will result in the blowing of the whistle.

At the same time, particular attention is called to the fact that operation of the rod 10 and whistle by either means 11 or 12', is per- 100

missible, without one means offering material resistance to operation by the other.

The result last mentioned may be accomplished also with the device of Figure 4 although the latter is of the modified form. In such form of Figure 4, the whistle B has a pneumatic cylinder 15^a and associated parts formed at the base thereof. This cylinder 15^a and associated piston and parts, in Figure 4 operate the valve of the whistle B, which valve has an arm or lever b similar to the lever a in Figure 1. The compressed air passes to the cylinder 15^a through a pipe 15', similar to the pipe 13, under control of a 10 foot-operated valve 12', located within the cab. The lever b has a pin 31' disposed in an elongated slot 36', of a rod 10, manually operable through manipulation of a lever 11, having a hand grip 12, the lever being pivoted 15 at 13' within the cab and pivotally connected at 14' to said rod 10. By providing the elongated slot 36' in rod 10 provision is made for operation of the whistle by valve 12' and its connected parts without actuation of lever 11. 20 Changes may be resorted to provided they fall within the spirit and scope of the invention.

I claim as my invention:—

In combination, a lever, a control rod fitted 30 to the lever and extending on opposite sides thereof, means operable by hand to actuate the control rod, pneumatic means to operate the control rod pivoted to said lever, the fulcrum of said lever occurring between said 35 pneumatic means and the pivotal connection of the control rod thereto, and means for controlling the pneumatic means located relatively close to the zone of operation of the operating means of the control rod.

40 In testimony whereof I affix my signature.
CHARLES D. RAFFERTY.
